[57] CLAIM

The ornamental design for a beverage cup, as shown and described.

DESCRIPTION

FIG. 1 is a top, front, and right side perspective view of a beverage cup showing my new design;

FIG. 2 is a right side elevation thereof, with the opposite side elevation being a mirror image thereof;

FIG. 3 is a front elevation thereof;

FIG. 4 is a rear elevation thereof; and

FIG. 5 is a top plan thereof.

The bottom of the beverage cup is unornamented.
